DESIGN FOR A DRESS

Rose Feintuck, New York, N. Y.

Application June 24, 1940, Serial No. 93,226

Term of patent 3½ years

To all whom it may concern:

Be it known, that, I, Rose Feintuck, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design;

Fig. 2 is a rear view of Fig. 1 on a reduced scale, and

Fig. 3 is an enlarged fragmentary view illustrating a portion of the shirred stitched trimming. The design is characterized by the combination on the dress disclosed of the specific shirred and stitched trimming arranged thereon as shown.

I claim:

The ornamental design for a dress, substantially as shown and described.

ROSE FEINTUCK.
